Des. 222,897
Patented Jan. 25, 1972

222,897

INTRUSION ALARM DEVICE

Maurice Y. White, Overland Park, Kans., assignor to
P. R. Mallory & Co. Inc., Indianapolis, Ind.

Filed June 1, 1970, Ser. No. 23,215

Term of patent 14 years

Int. Cl. D29—99

U.S. Cl. D72—1

FIG. 1

FIG. 2

FIG. 3

FIG. 4

FIG. 1 is a front perspective view of an intrusion alarm showing my new design;

FIG. 2 is a front elevational view thereof;

FIG. 3 is an elevational view of the side opposite that shown in FIG. 1;

FIG. 4 is a bottom plan view.

The indicia is shown in broken lines in FIGS. 1 and 2 for illustrative purposes only.

I claim:

The ornamental design for an intrusion alarm, substantially as shown and described.
